UNITED STATES PATENT OFFICE.

JOHANN JAKOB HUBER, OF TUTTLINGEN, GERMANY, ASSIGNOR TO JOSEPH KUHN, OF CHICAGO, ILLINOIS.

ADVERTISING DEVICE.

Application filed September 12, 1927. Serial No. 219,107.

The present invention concerns a novel form of advertising device which is operated by the movements of a door, gate, window, or the like, and which comprises a 5 pivotally mounted semaphore bearing advertising indicia which may be integral with, painted or printed upon, or removably connected with the arm of said semaphore, and also comprising an opaque cover to 10 conceal the said semaphore when in one position, and means for throwing said semaphore into a visible position upon the operation of the said door or gate.

Some of the particular advantages residing in the device which is the subject of my present invention are the comparatively sudden flashing into view, approximately at the height of vision of a person opening a door, of a semaphore bearing an advertisement, 20 so that the said advertisement will be more or less forcibly called to the attention of the person operating the door, thus making the advertisement much more effective than if it were merely painted or otherwise applied to the glass or surface of the door.

Another object of my invention is to provide an opaque cover or housing to contain said semaphore when the door is closed and which cover may also bear suitable advertising indicia.

Devices are known in which swinging advertising signs are applied to doors and are operated by the opening or closing of the door, but in all of these devices the advertising sign is visible both in its horizontal and vertical position, and, obviously, if the reading matter is in its normal position when the sign is horizontal it will not be easily read when the sign is in the vertical 35 position; and hence the advertising value of such a sign is only about one-half that of the advertising sign which is constructed in accordance with my present invention.

For example, the opaque cover concealing 45 the semaphore may also bear suitable advertisements which would be so applied as to be legible and readable when the door is closed, and it is also within the scope of my invention to have one type of advertising 50 sign attached to the opaque cover and another sign to the semaphore.

Another object of my invention is to provide a semaphore arm which is slotted, or otherwise rendered adaptable for the ready

insertion, attaching and removal of advertising indicia so that the latter may be changed at suitable intervals without in any way affecting the action or installation of my present advertising device.

One exemplification of my invention is 60 illustrated in the hereunto annexed drawings, in which

Figure 1 is a partially sectional and front elevational view of my device, showing the same attached to a door and the frame 65 thereof;

Fig. 2 is a partial side elevational view showing one of the means for operating or moving the said semaphore;

Fig. 3 is a sectional and partial elevational side view showing the method of swinging the said semaphore and also the means employed for insuring its ejection from the vertical position and the means for limiting its downward movement at the horizontal position;

Fig. 4 is a partial sectional view of the support and shaft along the line IV—IV of Fig. 1, looking downwards; and

Fig. 5 is a perspective view of an inclined 80 plane co-operating with a roller which actuates the pull rod connected with the semaphore.

Figure 6 is a sectional view of a modification.

My advertising device is normally attached, as shown in Fig. 1, to a door 1, being secured thereto by a supporting and mounting plate 2 near the edge of the door by means of screws passing through the screw-holes 3. The said plate which may be conveniently made of metal stamped to conform to the desired shape, is connected to the semaphore 4 by means of the pivot 5.

The semaphore arm is provided with a 95 flanged frame 6 which may bear a suitable advertising sign 7 having indicia 8. There is also provided an arm 9 pivoted to the semaphore 4 by the pivot 10 and which arm is connected to a rod 11 threaded at the 100 upper end thereof 12 and which part is screwed into a slotted shaft 13 which bears a roller support 14 having a roller 15 at the upper end thereof. A guide 16 attached or integral with the supporting plate 2 serves 105 to guide the rod 11 and also to retain in the compressed position a spring 17 which is wrapped around the rod 11, and which by

being retained by the flange head of the arm 9 will tend to turn the semaphore about its pivot if the same should be in the vertical position, and therefore tend to throw it into the horizontal position, this movement being aided and accelerated by gravity.

In order to conceal the semaphore 4 when it is in the vertical position as it appears in Fig. 3, and in dotted lines in Fig. 1, there is provided an opaque cover 18 which is attached to the said back supporting plate 2 and spaced therefrom a sufficient distance to permit of the entrance of the semaphore 4 by means of a plurality of machine screws 19 having sleeves 20 thereon and which screws engage suitable threaded holes 21 in the supporting plate 2. Two of the said sleeves 20 may be made of resilient material such as rubber, and perform a dual function of spacing the opaque cover 18 from the said back plate 2, and also to limit the motion of the semaphore 4 from substantially the vertical to substantially the horizontal position. As for instance, in Fig. 1, the screw 19 with its sleeve 20 prevents the further downward movement of the semaphore 4 thus keeping it in substantially a horizontal position and in which position the advertising indicia will be readable.

In order to retract the semaphore 4 from the horizontal position to the vertical position an inclined plane 22 integral with a supporting plate 23 is attached to the door frame 24 by screwing the same to the said door frame. It will be seen that the roller 15 while out of engagement with the incline 22 when the door is open will engage the same when the door starts to close, as shown in Fig. 2, and while riding up the incline 22 will exert an upward pull upon the shaft 13 and the rod 11 so that the semaphore 4 will be pulled into a substantially vertical position, while at the same time the spring 17 will be placed under compression. Inasmuch as the rod 11, which is threaded at its upper end 12 for a substantial distance, is screwed into a threaded central opening in the shaft 13, the length of the said shaft and rod can be accurately controlled so as to insure complete movement of the semaphore 4 from one position to the other. The shaft 13 is guided by a guide 25 integral with a flange 26 which is attached to the extreme upper portion of the door, and which shaft-guide has at one side of the interior a suitable projection 27 engaging a slot 28 in the said shaft 13 to prevent the same from turning and limiting the same to an up-and-down reciprocating motion. This is necessary in order to prevent a change in the effective length of the combined rod, shaft, and roller support so that when the device has once been fastened to the door and adjusted, it will continue to function at every opening and closing of the door. This

construction is more clearly shown in the enlarged cross-sectional view shown in Fig. 4.

If the door 1 closes flush with its frame 24 then the incline 22 with its supporting flange 23 is secured flush against the frame. If, however, the construction of the door is substantially as in Fig. 2, it will be necessary to space part 23 a distance away from the sill 29 (Fig. 2) to a thickness equal to the thickness of the part of the door that does not enter the frame. Alternatively, as shown in Fig. 6, the incline 22 may be somewhat altered in shape and an opening may be cut in the door to allow the incline 22 to pass through the door when the same is closed. This type of construction is necessary if the device is to be attached to the inside of an outwardly swinging door.

In order to allow of the changing of the advertising sign 7 retained within the peripheral groove 6 of the semaphore 4, a small projection 30 is formed on the said semaphore, it being contemplated that the advertising sign 7 being of such flexible nature as for example paper or the like, may be pushed over the said projection to the extreme end of the peripheral groove 6 and may be kept from falling downwards when the semaphore is in the vertical position by the said projection 30.

The opaque cover 18 may be either left blank, or, more suitably, provided with advertising lettering or the like. In order to make my device applicable to both right and left hand doors, the pivot 10 on the semaphore 4 has a counterpart 10' so that by simply changing the pivotal connection from 10 to 10' and turning the semaphore 4 180° about its pivot it may be applicable to a door opening in a sense opposite to that shown in Fig. 1.

In order to allow the semaphore 4 to enter the vertical position, one of the screws 19, (in Fig. 1) namely the screw 19', is merely a dummy screw so as to preserve the symmetrical and ornamental appearance of the opaque cover 18. If the device is to be used on a door opening in a sense opposite to that shown in Fig. 1, then this screw is transferred to a position immediately opposite and on a horizontal line with said screw 19'.

The operation of my device as applied to a right-handed inwardly opening door upon the inside thereof, substantially as shown in Fig. 1, is as follows: When the door is in the closed position the roller 15 will be at the top of the incline 22, and therefore the shaft 13 and the rod 11 will be pulled upwardly and the semaphore will point in vertical direction with its pivot at its lowest point, as shown in the dotted lines in Fig. 1, and neither the semaphore nor the retaining supporting plate 2 nor the opaque cover 18 will be visible from the outside of

the door but the opaque cover will be visible from the inside of the door, concealing the semaphore 4.

On opening the door, the roller 15 will move downwardly along the incline 22; the rod 11 will move downwardly and the spring 17 will exert a push against the semaphore 4, causing the same to move sidewardly and to the right, and thereupon, by virtue of the combined effect of the spring 17 and of gravity, fall into a horizontal position. The semaphore 4 will be stopped at the point where it is in a horizontal position by the sleeve 20 upon the lower right hand screw 19.

Upon closing the door, the roller 15 will ride upwards on the incline 22 and will pull the semaphore up and back behind its opaque cover 18. The method of attaching the device to the door is plainly shown in the hereunto annexed drawings, and it is believed that the operation of my device will be fully understood from the herein contained description and drawings. I have produced by means of my present invention, a highly novel and useful form of advertising device which presents the following advantages over any similar device known to me, namely by providing an advertising semaphore:

- (1) In which the particular advertisement may be changed at will;
- (2) In which the advertisement is never presented except right side up and in legible position;
- (3) In which means are provided for a separate advertisement upon the opaque cover;
- (4) Which is very easily attached and adjusted to any style of door;
- (5) Which is particularly simple in construction and, therefore, can be made rugged without making it expensive; and
- (6) In which the suddenness of the appearance of the semaphore increases the attention compelling value of the advertisement.

Obvious modifications in the construction of my device, such as for example as having

the semaphore spring from a horizontal to a vertical position so as to hang downwardly over the top of the door, or the use of translucent signs therein, or of such mechanical equivalents as will occur to a mechanic, are within the scope of my invention, which is to be interpreted and limited only by the hereunto appended claims as viewed in the light of the prior art.

I claim as my invention:

1. An advertising device comprising a housing fastened to a door, a semaphore pivoted within said housing and concealed therein when the semaphore is in one position, a stop limiting the movement of said semaphore when in a position substantially at right angles to the first position, and means operable by the opening and closing of the door to actuate said semaphore.

2. In an advertising device, the combination of a housing attachable to either side of a door, a semaphore pivoted within said housing, an operating shaft attached to said semaphore, a compression spring surrounding said shaft and biasing said semaphore toward a horizontal position, and means operated by the closing of said door to bring the semaphore into a vertical position.

3. In an advertising device, the combination of a plate attached to a door, a semaphore pivoted to said plate, flanges on said semaphore for holding a removable sign, stops limiting the movement of a semaphore substantially from the vertical to the horizontal position, a roller support and shaft attached to said door, a rod connecting said semaphore and shaft, a compression spring surrounding part of said rod and tending to move said semaphore from the vertical position, an inclined plane attached to a door frame engaging said roller when the door is closed, and an opaque cover concealing said semaphore when in the vertical position.

In witness whereof, I have hereunto subscribed my name.

JOHANN JAKOB HUBER.
